UNITED STATES PATENT OFFICE.

EDWARD M. STILES, OF BURLINGTON, IOWA, ASSIGNOR TO U. S. SLICING MACHINE COMPANY, OF LA PORTE, INDIANA, A CORPORATION OF INDIANA.

WORKHOLDER FOR SLICING MACHINES.

Original application filed July 2, 1918, Serial No. 243,022. Divided and this application filed August 25, 1919, Serial No. 319,782. Renewed November 20, 1922.

To all whom it may concern:

Be it known that I, EDWARD M. STILES, a citizen of the United States, residing at Burlington, in the county of Des Moines and 5 State of Iowa, have invented certain new and useful Improvements in Workholders for Slicing Machines, of which the following is a specification.

The object of this invention is to provide 10 a device of the class named which shall be of improved construction and operation. The invention is exemplified in the combination and arrangement of parts shown in the accompanying drawings and described in 15 the following specification and it is more particularly pointed out in the appended claims.

In the drawings—

Fig. 1 is a rear elevation of one form of 20 work-holder embodying the present invention.

Fig. 2 is a top plan view partly in section on line 2—2 of Fig. 1.

Fig. 3 is a fragmentary vertical section 25 on the line 3—3 of Fig. 1.

This application is a division of application Serial No. 243,022, filed July 2, 1918, patented December 20, 1921, No. 1,400,698.

In slicing machines of the usual form 30 there is provided a reciprocating table shown at 10 in the drawings upon which a sliding work-holder or meat plate 11 is mounted. The material to be sliced is placed on the plate 11 and held during the 35 slicing operation by a clamp or holder of the same form. It is usual to provide the edge of the table 10 which passes adjacent the slicing knife during the slicing operation with a corrugated plate 12 which supports the portion of the meat or other material being sliced projecting toward the slicing knife. After a piece of material has been almost completely sliced it is impossible to longer clamp the material upon the 40 meat plate 11 by a clamp which bears upon the upper face of the material, and the present invention provides means for engaging the face of the material opposite that from which the slices are being cut, for the purpose of forcing the material downwardly 45 upon the plate 12, so that its bottom surface may be firmly held against the plate while at the same time the rear surface is also grasped and held in position. When meat 50

or other material is being held in this way 55 for cutting the last slices it is of great advantage to have the meat firmly held against the corrugations on the plate 12 for the reason that the portion of the meat projecting forwardly from the holder is held against 60 lateral pressure of the slicing knife by the corrugations in the plate on which it rests.

In the form of the invention shown in this application the material is forced downwardly into engagement with the corrugated 65 plate 12 by pivotal movement of engaging teeth supported on the holder in a manner to be described.

In the drawings the numeral 33 designates a front plate rigidly secured to bars 15 70 which form the frame of the work-holder. The plate 33 is provided with a plurality of slots 34 having lugs 35 extending rearwardly from the edges thereof and pins or teeth 36 supported on pivots 37 between the 75 lugs 35. Each pin 36 is provided with a rearwardly projecting bifurcated portion 38 which engages a pin 39 carried between spaced upright bars 40 arranged to move vertically in the rear of the plate 33. The 80 bars 40 are all connected by cross bars 41 and 42 which have their ends guided in slots formed on the inner faces of the upright frame members 15. A pair of links 43 is pivoted to lugs 44 connected with the cross 85 bar 41, and the upper ends of the links 43 are connected with the prongs 45 of an operating lever 46 by pivot pins 47. The lever 46 is fulcrumed at 48 on lugs 49 carried by the upper cross bar 16 of the holder frame. 90 A handle 50 may be attached to the bar 16 for lifting the holder. The lever 46 and lugs 49 are provided with shoulders 51 and 52 for limiting the downward movement of the lever 46. In operation the lever 46 is 95 held in its uppermost position so that the pins 36 extend horizontally. The meat to be sliced is then placed upon the upper surface of the corrugated plate 12 and prongs 36 are 100 caused to penetrate the meat sufficiently to permit the rear face of the meat to engage the front face of the plate 33. The lever 46 is then swung downwardly into the position shown in broken lines in Fig. 3, which movement tilts the prongs 36 downwardly, 105 as indicated in that figure, and thus draws the meat tightly into engagement with the front face of the plate 33 and at the same

time forces it firmly into contact with the upper corrugated surface of the plate 12. The lever 46 and links 43 are preferably so related to one another that the lever will 5 pass dead center just before it reaches the limit of its downward movement, and in this way the pins are locked in their downward position.

I claim:

- 10 1. A work holder for slicing machines comprising an upright frame having an abutment plate thereon, a plurality of teeth pivotally mounted on said frame and arranged to project forwardly from said plate when in suitable position to receive material to be sliced as it is moved against said plate, and means for shifting said teeth upon their pivots in a direction substantially normal to the longitudinal axis of said pins to cause them to clamp said material against said plate.
- 15 2. A work-holder for slicing machines, comprising an upright plate, a plurality of substantially straight pins projecting forwardly from said plate and pivotally mounted thereon, and means for shifting said pins about their pivots to cause them to clamp material against said plate.
- 20 3. In a slicing machine, a work-supporting table, a work-holder mounted on said table and having an upright plate, a plurality of pivotally mounted pins projecting forwardly from said plate in position to enter material as it is moved against said plate, and means for moving the forward ends of said pins downwardly about their pivots and transversely of their length to cause them to press material against the upper face of said work-supporting table and to clamp said material against said plate.
- 25 4. A work-holder for slicing machines, comprising a frame having stationary pivots thereon, work-engaging pins each separately mounted on one of said pivots, and a secondary frame movably mounted on said first mentioned frame and engaging said pins to shift said pins upon their pivots and to cause them to press material engaged thereby against the face of said frame.
- 30 5. A work-holder for slicing machines, comprising a frame having an upright bearing surface, pins pivotally mounted on said frame and projecting at all times through openings in said surface, and a movable member carried by said frame in the rear of said surface and engaging said pins to cause said pins to move about their pivotal supports to press material engaged thereby against said upright bearing surface.
- 35 6. A work-holder for slicing machines, comprising a support for material to be

sliced, a frame arranged in an upright position above said support, substantially straight pins pivotally mounted on said frame and movable into position to extend substantially horizontally therefrom, and mechanism for tilting said pins downwardly into an inclined position to cause said pins to depress material engaged thereby against 65 said work-support and against the face of said upright frame.

7. The combination with a work-support for slicing machines, of a work-holder having an upright bearing surface arranged above said support, work-engaging pins pivotally mounted on said holder and projecting from the work-engaging face thereof substantially normal thereto when in work-receiving position, means for swinging 75 said pins downwardly about their pivotal support on said work-holder from a substantially horizontal to an inclined position, and means for locking said pins in said inclined position.

8. A meat end grip for slicing machines comprising a supporting frame having an upright abutment plate, tines supported by said frame and projecting at all times through openings in said plate to engage 90 material to be held, and a tine actuating frame member movable relative to said supporting frame and engaging said tines to cause them to grip material and hold it against said abutment plate.

9. A meat end grip for slicing machines comprising a supporting frame having an upright abutment plate thereon, pointed tines movably mounted on fixed supports and projecting at all times through slots in 95 said abutment plate, a tine actuating frame arranged in the rear of said abutment plate and movable relative thereto substantially in the direction of the plane thereof, means on said actuating frame for engaging said tines to move said tines in said slots to cause them to hold material against said abutment plate, and means for retaining said frame and tines in holding position.

10. A meat end grip comprising an upright abutment member having openings therein, tines supported by said member and extending therethrough, the support for said tines permitting vertical movement of the portion thereof projecting from the front 115 of said abutment member, a tine operating frame slidably mounted in the rear of said abutment member and engaging said tines to move said tines in said openings, and means for actuating said frame.

In testimony whereof I have signed my name to this specification on this 21st day of August, A. D. 1919.

EDWARD M. STILES.
